United States Patent Office

Des. 180,423

Patented June 4, 1957

180,423

NOVELTY EARRING BOX

Robert C. Rutledge, Norfolk, Va.

Application September 17, 1956, Serial No. 42,970

Term of patent 14 years

(Cl. D86—9)

Fig. 1

Fig. 2

Fig. 2 is a top plan view thereof; and

Fig. 3 is a side elevational view looking from the right of Fig. 1 but showing the cover in the open position.

I claim:

The ornamental design for a novelty earring box, substantially as shown.
